UNITED STATES PATENT OFFICE.

ISAAC ELVIN DEADMOND, OF NEWKIRK, OKLAHOMA.

FUEL-LOCK.

1,311,863.

Specification of Letters Patent.

Patented July 29, 1919.

Application filed November 16, 1917. Serial No. 202,343.

To all whom it may concern:

Be it known that I, ISAAC ELVIN DEADMOND, a citizen of the United States, residing at Newkirk, in the county of Kay and 5 State of Oklahoma, have invented certain new and useful Improvements in Fuel-Locks, of which the following is a specification.

This invention relates to fuel locks for 10 internal combustion and like motors and it is the principal object of the invention to provide a fuel lock especially adapted for use in connection with motor driven vehicles whereby the flow of fuel through the intake 15 manifold to the motor can be discontinued by the operator when leaving the vehicle and locked in order that the theft of the same will be prevented during his absence.

It is also an object of the invention to 20 provide a simple, durable and compact locking means for the fuel controlled valves whereby the same can be locked in closed position and freely opened when desired.

Other objects will be in part obvious and 25 in part pointed out hereinafter.

The invention consists, furthermore, in the novel arrangement and combination of the parts of the lock, as well as in the details of the construction of the same, all of 30 which will be more fully described in the following specification, and then finally embodied in the clauses of the claim, which are appended to the specification and which form an essential part of the same.

The invention is clearly illustrated in the 35 accompanying drawings, in which:—

Figure 1 is a front elevation of a valve provided with the improved lock, portions of the same being in section.

Fig. 2 is a horizontal section therethrough, and,

Fig. 3 is a detail in perspective of the valve spindle.

Having more particular reference to the 45 drawings and in connection with which like reference characters will designate corresponding parts throughout the several views thereof, 1 represents the base plate or body of the valve, the same being provided with 50 a centrally disposed opening 2 and other smaller openings 3, which as will be understood, receive bolts or like fastening devices therethrough when the said plate is interposed in the intake manifold of a combustion motor.

Formed integral with the upper portion of the plate 1 is a casing 4 having oppositely disposed vertical bores formed therein, one of which rotatably receives the spindle 5 of the usual butterfly type of valve 6 mounted so as to control the passage of fuel through the opening 2 into the manifold and combustion motor. In this connection, it is to be noted that the spindle 5 is provided with a barrel 7, the same being of a 65 size and shape complementary to the bore and being snugly received thereby. A pocket or keeper 8 is formed in the peripheral surface of the barrel 7 and is adapted to align with a way 9 formed in the side wall of the 70 said bore and communicating with the adjacent bore.

Rotatably mounted in the remaining bore is the barrel element 10 of a lock, the lower portion of which is recessed as at 11 and has 75 pivotally mounted therein a bolt or locking pin 12 adapted to be passed through the way 9 into engagement with the keeper 8, at times, said pin being formed with a curved bearing head 12' engaged by a spring 12", 80 the tendency of which is to move the free end of the pin outwardly so that it will normally tend to engage in the way 9 and the keeper 8 upon rotation of the barrel element. A key receiving way may be and preferably 85 is formed in the upper portion of the barrel 10 and obviously, permits the introduction of a key thereto in order that the said barrel may be turned. Thus, when the barrel 10 is turned clockwise the locking pin 12 90 which is pivotally mounted thereon will be caused to move outwardly into engagement with the way 9, by reason of a spring 12" arranged in the said recessed portion 11 and normally bearing thereon. As a consequence, 95 the locking pin will pass into engagement with the keeper 8 and thereby prevent the rotation of the butterfly valve 6.

From the foregoing, it will be readily understood by those skilled in the art that 100 I have provided an efficient form of fuel lock whereby the supply of fuel through an intake manifold to a combustion or like motor may be discontinued at will by the operator and locked in its closed position to 105 prevent tampering or undue operation of the same by unauthorized persons. The device, by reason of its positive operation and compact form is especially adapted for use in connection with motor driven vehicle, 110

affording an effective means for preventing theft of the vehicle during the absence of the operator or owner.

Manifestly, the construction shown is capable of considerable modification and such modification as is within the scope of my claim, I consider within the spirit of my invention.

I claim:

10 In combination with the fuel feed pipe of a motor, a valve casing interposed therein, a casing arranged on the valve casing having a plurality of vertically disposed bores therein, one of said bores receiving a valve 15 spindle therein, said valve spindle having

a keeper therein, a rotatable barrel in the remaining bore having a recessed portion, a locking pin formed with a curved bearing head pivoted to the barrel and having said bearing head engaged in the recessed portion 20 thereof, and a spring engaged with the curved bearing head normally tending to move the free end of the locking pin outwardly through a bore communicating with said vertically disposed bores into the first 25 bore and in engagement at times with said keeper upon rotation of the barrel.

In testimony whereof, I affix my signature hereto.

ISAAC ELVIN DEADMOND.
